UNITED STATES PATENT OFFICE.

WICTOR OSKAR JULIUS ANDERSSON, OF MALMÖ, SWEDEN.

CALCULATING-MACHINE.

1,353,504.

Specification of Letters Patent. Patented Sept. 21, 1920.

Application filed August 16, 1918. Serial No. 250,158.

To all whom it may concern:

Be it known that I, WICTOR OSKAR JULIUS ANDERSSON, a subject of the King of Sweden, residing at Malmö, in the county of 5 Malmöhus and Kingdom of Sweden, have invented new and useful Improvements in Calculating-Machines, of which the following is a specification.

My invention relates to calculating machines in which calculations are performed by means of setting disks having teeth which are manually adjustable by means of rotatable adjusting disks.

An object of my invention is the provision of a calculating machine of this class in which the operator can simultaneously reset to zero position all of the setting disks and adjusting disks.

In carrying out my invention, I provide 20 a plurality of pinions secured upon a common shaft for simultaneous movement and which coöperate with teeth on the setting disks so that by rotation of the pinions, the setting disks can be returned to the zero position. The shaft for the pinions is movable longitudinally so that the pinions may be moved into or out of mesh with the setting disks, the mechanism for shifting the 25 shaft being operable automatically upon rotation thereof.

I will describe one form of mechanism embodying my invention, and will then point out the novel features thereof in claims.

35 In the accompanying drawings, Figure 1 is a sectional view taken on the line A—A of Fig. 2, and showing one form of mechanism embodying my invention.

Fig. 2 is a view showing in front elevation the mechanism shown in Fig. 1 in normal position, a portion of the casing being broken away.

Fig. 3 is a view similar to Fig. 2, showing the mechanism in active position.

45 Fig. 4 is a vertical sectional view taken on the line B—B of Fig. 2, and showing the adjusting disk in normal position.

Fig. 5 is a view similar to Fig. 4 with the adjusting disk revolved part of its way 50 toward the zero position.

Figs. 6 and 7 are cross sectional views of the adjusting disks 17.

Fig. 8 is a view similar to Fig. 5 showing one adjusting disk in zero position.

55 Fig. 9 is a vertical sectional view illustrating the mechanism for connecting the

totalizers to the mechanism forming the subject matter of the present invention.

Similar reference characters refer to similar parts in each of the several views.

Referring specifically to the drawings, 1 designates the setting disks which are rotatably mounted upon a shaft 10 suitably journaled in a casing 13. The setting disks 1 are of the usual type having the teeth 2 which are adjusted by means of the adjusting disks 3. The adjusting disks 3 are fixed to the shaft 10 and are provided with operating handles 22, whereby the disks are oscillated to adjust the teeth 2 in a manner which is well understood in the art. A major portion of the periphery of each disk 3 is provided with teeth 4, which, as shown in Figs. 3 and 4, mesh with pinions 5 fixed at regular spaced intervals to a shaft 6 journaled in 65 bearings 8 supported upon the base plate 7. As shown in Figs. 2 and 3, the left hand end of the shaft 6 is provided with a cog wheel 9 fixed to the shaft for rotation thereof. Loosely fitted on the shaft 10 at a point 70 directly above the cog wheel 9 is an operating disk 11 which is provided with teeth 110 which mesh with the teeth of the cog wheel 9, as illustrated to advantage in Fig. 1. The operating disk 11 is adapted to be 75 manually oscillated by means of an arm 12 secured to the disk and projecting through a suitable slot formed in the casing 13. As shown in Fig. 1, the disk is biased to normal position by means of a coil spring 21, so 80 that when moving the disk from the position shown in Fig. 1, such movement is against the tension of the spring. Mounted on the right hand side of the cog wheel 9 is a pawl 14 which is biased into engagement with a ratchet 16 by means of a 85 spring 15.

The arrangement of the pawl and ratchet is such that the shaft 6 is free to rotate in a clockwise direction, as viewed in Fig. 1, independently of the cog wheel 9, but when rotated in the opposite direction, the pawl 14 engages the ratchet 16, thus locking the cog wheel to the shaft and causing the two to 90 rotate together.

The shaft 6 is mounted in such a manner that it is capable of being shifted longitudinally so that the pinions 5 may be thrown into or out of mesh with the adjusting disks 3. When the shaft is in either extreme position, the cog wheel 9 meshes with the operating disk 11, it being noted that the thickness 95

of the cog wheel is equal to or greater than the shifting movement of the shaft 6. When the shaft 6 is in the normal position, as shown in Fig. 2, the pinions 5 are disaligned 5 with relation to the adjusting disks 3, but when the shaft 6 is shifted to the active position as shown in Fig. 3, the pinions 5 move into mesh with the teeth 4 of the disks 3. The shifting of the shaft 6 from normal to 10 active position is accomplished by the mechanism which is actuated upon the rotation of the shaft 6 through the cog wheel 9 and the operating disk 11. This mechanism is as follows:

15 As shown in Figs. 2 and 3, the right hand end of the shaft 6 is provided with a cam 17 having the outer edge thereof formed with a recess 170, one wall of which is inclined as at 20, as clearly shown in Figs. 6 and 7. Secured to the base plate 7 is a pin 18 which normally lies within the recess 170, as shown in Fig. 2. Surrounding that portion of the shaft 6 which extends from the right hand bearing 8 to the cam 17 is a torsional spring 25 19 which serves to bias the shaft 6 to the normal position, as shown in Fig. 2. From this arrangement, it will be seen that upon rotation of the shaft 6 in such a direction that the pin 18 engages the inclined wall 20, 30 the pin in attempting to move out of the recess on the inclined wall forces the cam 17 and, consequently, the shaft 6 to the left against the tension of the spring 19 so that the shaft occupies the position shown in 35 Fig. 3.

From the foregoing description taken in conjunction with the accompanying drawings, the operation of the mechanism will be readily understood from the following brief 40 description:

Assuming that the setting disks 1 have been moved to various positions to calculate certain values, and the adjusting disks occupy corresponding positions, it is now desired to return the setting mechanism to 45 zero position. To secure this restoration of the mechanism, the operating disk 11 is partially rotated in the direction indicated by the arrow 11 in Fig. 1, whereby the pinion 9 together with the shaft 6 are rotated in the direction indicated by the arrow 1 in Fig. 1. With the rotation of shaft 6, the latter is shifted from the normal position to 50 the active position so that the pinions 5 now mesh with the teeth 4 of the adjusting disks 3. Upon continued movement of the operating disk 11 to the final position, the pinions 5 now rotate the adjusting disks 3 in the direction indicated by the arrow in Fig. 4, 55 whereby the disks 3 and consequently the setting disks 4 are returned to zero position.

During the movement of the arm 12, from the starting position to the final position, as shown in Fig. 8, the shaft 6 has completed 60 one revolution, so that the pin 18 again rests

within the recess 170. Upon releasing the operating disk 11, the spring 21 returns the same to normal position without rotating the shaft 6, as the cog wheel now rotates independently of the shaft.

In Fig. 9 is illustrated the mechanism above described connected to the totalizers. Upon rotation of the setting disks on the shaft 10, the values set on the setting disk 1 are transmitted by means of gears 23 mounted on a stationary shaft 26, to gears 24 of the totalizers. The gears 24 are loosely mounted on the shaft 27, and have rigidly secured thereto wheels or disks 28 provided on their peripheries with the characters 1 70 to 9 and the "0" sign. The totalizers together with the transmission gears 23 and the shaft carrying the numeral disks 28 and their gears 24 are all mounted on a carriage 25, which is tongue-and-groove connected 75 with a recess in the base plate 7 for slidable movement therein in direction parallel with the shaft 10, so that the disks 28 can be brought to alignment with the setting disks. 80

Although I have herein shown and described only one form of mechanism embodying my invention, it is to be understood that various changes and modifications may be made herein without departing from the spirit of the invention, and the spirit and 90 scope of the appended claims.

What I claim is:

1. In a calculating machine, a setting mechanism comprising a plurality of setting disks, a plurality of disks for adjusting said 100 setting disks to indicate certain values, and means for simultaneously returning all of said disks to normal position after they have been adjusted.

2. In a calculating machine, a setting mechanism comprising a plurality of setting disks, a plurality of disks for adjusting said setting disks, and means for simultaneously actuating all of said adjusting disks to return the setting disks to normal position. 105

3. In a calculating machine, a setting mechanism comprising a plurality of setting disks and adjusting disks for operating the setting disks, a plurality of pinions adapted to actuate said adjusting disks, and means 115 for moving said pinions into and out of engagement with the adjusting disks.

4. In a calculating machine, a setting mechanism comprising a plurality of setting disks and adjusting disks for operating the setting disks, a longitudinally movable shaft, a plurality of pinions fixed to said shaft and adapted to actuate said adjusting disks, means for shifting said shaft to cause said pinions to engage and disengage said 120 adjusting disks, and means for rotating the pinions.

5. In a calculating machine, a setting mechanism comprising a plurality of setting disks and adjusting disks for operating the 130

setting disks, a longitudinally movable shaft, a plurality of pinions fixed to said shaft and adapted to actuate said adjusting disks, means for rotating said shaft, and 5 means operable when said shaft is rotated to move the pinions into engagement with the adjusting disks.

6. In a calculating machine, a setting mechanism comprising a plurality of setting 10 disks and adjusting disks for operating the setting disks, a longitudinally movable shaft, a plurality of pinions fixed to said shaft and adapted to actuate said adjusting disks, means for rotating said shaft, and means 15 operable when said shaft is rotated to move the pinions into engagement with the adjusting disks.

7. In a calculating machine, a setting mechanism comprising a plurality of setting 20 disks and adjusting disks, a longitudinally movable shaft, pinions fixed to said shaft and adapted to actuate said adjusting disks,

means for biasing said shaft to a position wherein said pinions disengage the adjusting disks, means for rotating said shaft, 25 and means responsive to the rotary movement of said shaft for shifting the latter to cause said pinions to engage the adjusting disks.

8. In a calculating machine, a setting 30 mechanism comprising setting disks and adjusting disks, a longitudinally movable shaft, pinions fixed to said shaft and adapted to actuate said adjusting disks, a gear mounted on said shaft for rotation therewith in one direction, manually operable 35 means for rotating said gear, and cam actuating means responsive to the rotation of said shaft for shifting the latter to cause the pinions to engage or disengage the adjusting disks.

In testimony whereof I have affixed my signature.

WICTOR OSKAR JULIUS ANDERSSON.
